UNITED STATES PATENT OFFICE.

FRED H. MILLER AND PETER LARSON, OF CROOKSTON, MINNESOTA.

LOG-CARRIAGE.

SPECIFICATION forming part of Letters Patent No. 659,036, dated October 2, 1900.

Application filed December 7, 1899. Serial No. 739,479. (No model.)

To all whom it may concern:

Be it known that we, FRED H. MILLER and PETER LARSON, citizens of the United States, residing at Crookston, in the county of Polk and State of Minnesota, have invented certain new and useful Improvements in Log-Carriages; and we do hereby declare the following to be a full, clear, and exact description of the invention, such as will enable others skilled in the art to which it appertains to make and use the same.

Our invention relates to log-carriages for sawmills, and has for its object to provide an automatic device for offsetting the logs by moving the same laterally, together with certain parts which support the log at the limits of the carriage's movement or as the movement of the carriage is being reversed.

More specifically stated, our invention has for its object to provide a simple, reliable, and efficient mechanism whereby at one limit of the carriage's movement the log will be automatically moved laterally away from the saw, so that under the return movement of the carriage it will pass clear of and without engagement with the saw and at the other limit of the carriage's movement the log will be automatically returned or moved laterally toward the saw, so that the saw may act upon the log under its next succeeding feed movement.

Offsetting devices for log-carriages are universally employed in connection with sawmills involving band-saws; but they are serviceable also in sawmills employing circular saws.

By our invention we accomplish the desired offsetting movements of the log automatically and positively, regardless of the extent of movement given to the log-carriage, and by these automatic and positive actions all the dangers and objections incident to the rubbing of the log against the saw under the return movements of the carriage are eliminated or avoided.

The invention consists of the novel devices and combinations of devices hereinafter described, and defined in the claims.

The invention is illustrated in the accompanying drawings, wherein like characters indicate like parts throughout the several views.

Figure 1 is a plan view with some parts broken away, showing a sawmill involving a band-saw, log-carriage, and other parts to be hereinafter noted. Fig. 2 is a view in side elevation with some parts broken away and others sectioned, showing the parts of the sawmill illustrated in Fig. 1. Fig. 3 is a transverse vertical section taken approximately on the line $x^3 x^3$ of Figs. 1 and 2. Fig. 4 is a detail view, partly in side elevation and partly in vertical section, showing a portion of the log-carriage, a portion of the track or runway for the same, and one of the automatic offsetting levers or legs. Fig. 5 is a detail in transverse vertical section, taken approximately on the line $x^5 x^5$ of Fig. 4; and Fig. 6 is a plan view with some parts broken away and others removed, showing parts of a sawmill and illustrating a modified arrangement of the parts for effecting the offsetting movements of the log.

Of the parts of the sawmill illustrated the numeral 1 indicates the floor structure, on which track-beams 2, having track-rails 3 and 4, are secured in the ordinary manner.

The numeral 5 indicates the endless band-saw, which runs over suitable guide-wheels, a portion of one of which is indicated by the numeral 6. The guide-wheels for the band-saw 5 are mounted and driven in the ordinary or any suitable manner.

The numeral 7 indicates the frame proper of the log-carriage, and the numerals 8 and 9 indicate, respectively, the axles and wheels 85 of the log-carriage, the former of which are mounted in suitable bearings on the said truck-frame, and the latter of which run over the guide-rails 3 and 4, with which they co-operate in the ordinary manner, the wheels 90 at one side being grooved for engagement with the rails 4.

The numerals 10 and 11 indicate, respectively, the block and knee devices, which are of ordinary construction, the former being 95 mounted for movements transversely of the log-carriage in suitable guides or keepers 12 and the latter being mounted for transverse movements within the said blocks 10, which in turn serve as guides for the said knees. 100 The knees 11 are provided with the ordinary dog devices 13, which are operated by levers

14 in the ordinary manner. By means of the dog devices 13 14 the log y may be held in the ordinary manner and as indicated in Figs. 1, 2, and 3.

5 The ordinary or any suitable devices for imparting the successive lateral feed movements of the log y toward the saw 5 may be employed; but as our invention is not directed to this feature of construction such feed devices have been omitted from the drawings.

To impart the offsetting movements to the log with the block- and -knee construction above indicated, it has been customary to provide the so-called "blocks" 10 at their outer ends with laterally-spaced and depending lugs or fingers 15. (Best shown in Fig. 3.) In connection with these lugs 15 the log-carriage 7 was provided with a longitudinally-extended rock-shaft 16, mounted in suitable bearings 17 on the carriage-frame 7 and provided with cams 18, positioned to work one between the depending lugs 15 of each sliding block 10.

The construction so far described is old in the art, being what may be termed "standard" or "ordinary" construction, and in connection with such construction the rock-shaft 16 has been provided with a hand-lever, (not shown, but by means of which in accordance with the old practice the offsetting movements of the log were effected by hand by a person riding on the carriage.) With our invention, whereby the offsetting movements are automatically accomplished, such a hand-lever is unnecessary, and hence is not shown, although such a lever might be employed, as it would not interfere with the automatic actions and would make the offsetting devices operative either automatically or by hand. The mechanism which will now be described relates to our invention.

Pivoted at a to brackets a' on transverse beams a^2 , carried by the carriage-frame 7, is a pair of so-called "offsetting" legs or levers a^3 . These legs or levers a^3 are made up of telescoping sections a^4 and a^5 , the former of which are tubular and are rigidly but adjustably secured to the body portions of the said legs by nutted clamps a^6 . Coiled springs a^7 within the tubular sections a^4 yieldingly force the plunger-sections a^5 downward or outward, and the tension of these springs may be varied by set-screws a^8 , that work with screw-threaded engagements through the upper ends of the tubular sections a^4 and impinge against loose followers a^9 , that directly engage the upper ends of the said springs. Trip heads or shoes a^{10} are pivoted to the lower ends of the plunger-sections a^5 by bolts or pins a^{11} . These trip-heads a^{10} are recessed at their under side to receive friction blocks or brushes a^{12} , that are preferably made up of closely-laid strips of leather or rubber belting held in position by set-screws a^{13} , working through the ends of the heads a^{10} . Each

pivoted offsetting leg or lever a^3 works within a guide-bracket a^{14} , secured to the outer side of the carriage-frame 7 and provided at its opposite extremities with cushion-blocks a^{15} , formed, as shown, each of several strips of belting or similar material suitably secured together and within the said brackets. The pivoted heads a^{10} are rigidly connected by a long bar or strap a^{16} , and the under surfaces of the trip blocks or brushes a^{12} are preferably grooved to fit the upper surface of the track-rail 4.

Underneath the carriage-frame 7 is a bell-crank lever b , which is pivoted at its elbow directly to a bracket b' on a short longitudinal timber b^2 , which in turn is supported from transverse timbers b^3 , secured to the under portion of the carriage-frame 7. The outwardly-extended arm of the bell-crank lever b is attached by a slot-and-pin connection b^4 to a small bracket b^5 , secured on the intermediate portion of the strap or tie-bar a^{16} . The inner arm of the bell-crank lever b is adjustably connected to the inner end of a connecting rod or link b^6 by means of a pin, bolt, or similar device b^7 , adapted to be passed through any one of a series of holes b^8 in the said lever b . The outer end of the rod or link b^6 is pivotally connected to the free end of an arm b^9 , which is rigidly, but preferably adjustably, secured to a rock-shaft 16 by means of a set-screw b^{10} .

The operation of the mechanism above described will be substantially as follows: We will assume that the feed movement of the carriage is in the direction of the arrow marked z and that the return movement of the same is in the direction of the arrow marked z' on Fig. 1. With the various parts in the positions indicated in the drawings the carriage must be assumed to be running in the direction indicated by the arrow z' or to be making its return movement. Under this return movement of the carriage the offsetting legs or arms a^3 are thrown backward from the direction of travel by the friction blocks or brushes a^{12} , which slip frictionally over the rail 4. When the carriage reaches the limit of its return movement and begins its feeding movement in the reverse direction, the friction blocks or brushes a^{12} will adhere to the rail 4 with sufficient force to cause the pivoted legs or levers a^3 to reverse their inclination or to move to the opposite sides of their vertical positions or dead-centers, and to permit such movements the plunger-sections a^5 will be forced upward into the co-operating tubular sections a^4 against the tension of the springs a^7 . The movements of the offsetting-legs a , just described, acting through the tie-bar a^{16} , bell-crank b , and link b^6 , will move the arm b^9 and rock-shaft 16 far enough to turn the points of the cams 18 directly downward, and this movement of the cams will, as is obvious, force the

blocks 10, knees 11, and log y , held thereby, toward the saw 5. So far as the offsetting device is concerned, it would return the outer surface of the log y only into line with the saw 5; but the devices, such as usually employed, will in practice give an additional movement of the knees 11 with respect to the blocks 10, as before stated. At the limit of the carriage's feeding movement, or, rather, under the initial reversing movement of the carriage, the friction blocks or brushes a^2 by their engagement with the rail 4 will cause the offsetting-levers a^3 to be thrown back into the positions indicated in the drawings, and such movements of the levers will, through the connections already described, throw the cams back into the positions indicated in Fig. 3, thereby moving the sliding blocks 10, knees 11, and log y laterally away from the saw, so that the log under the return movement of the carriage will pass clear of the saw. It is of course evident that when the carriage is started in the direction in which the so-called "offsetting-levers" a^3 are inclined downward the friction blocks or brushes a^2 will not slip, for the reason that a downward pressure will be applied to them, from which downward pressure they will not be relieved until after they have passed their dead-centers with the rail 4, or, in other words, have been moved backward beyond their vertical positions, so that under the movement of the carriage the friction blocks or shoes a^2 will be dragged over the said rail 4.

With the automatic offsetting device above described it is obvious that the log will be properly offset by the initial movement of the log-carriage in either direction and that as the carriage is adapted to be given variable movements between any two points within the limits of the rails 3, 4 it follows that the offsetting movements will be positively given to the log always at the proper times while the log is moved in one direction or the other beyond the saw.

In the modification illustrated in Fig. 6 the carriage-frame 7 is itself adapted to be moved laterally on the axles 8, and the offsetting movements of the log will in this construction be accomplished by moving the carriage-frame 7 laterally to and from the saw. To accomplish the lateral movements, a bell-crank lever f is employed in lieu of the bell-crank lever b , previously described in connection with the construction illustrated in Figs. 1 to 5, inclusive. The elbow portion of this bell-crank lever f is pivoted at f' to a transverse beam f^2 of the carriage-frame 7, and the free end of the outwardly-extended arm of said lever f is attached to the bracket b^5 , previously described, by a slot-and-pin connection f^3 . The free end of the inner arm of the bell-crank lever f is shown as pronged and positioned to work between a pair of laterally-spaced collars f^5 on the axle 8. With

this construction the arrangement of the bell-crank lever f and its connections just described should be duplicated at both ends of the carriage or at each truck-axle. When the bell-crank lever f is vibrated in the one direction or the other, it finds its fulcrum or base of reaction against one or the other of the collars f^5 on the axle 8, and the carriage-frame 7 will be moved either toward or from the face of the saw to produce the proper offsetting movements of the log.

It will also be understood that the invention described is capable of many other modifications than those indicated or set forth within the broad scope of our invention. For instance, a single offsetting-lever might be employed to automatically effect the offsetting movements at the extremes of the carriage's movements, although a pair of said levers or legs operating together give the best results.

What we claim, and desire to secure by Letters Patent of the United States, is as follows:

1. The combination with a log-carriage, of an automatic offsetting device, involving a pivoted and extensible leg or arm, provided at its free end with a pivoted head or shoe adapted to slide over a longitudinally-extended rail, substantially as described.

2. The combination with a log-carriage, of offsetting mechanism, involving a pair of pivoted legs or levers having spring-pressed and extensible sections, friction shoes or heads pivoted to the extensible sections of said legs or levers and arranged to slide over a longitudinally-extended rail or guide, a tie bar or rod connecting said legs or levers for common pivotal movements, and connections between said connecting bar or rod and the log-operating devices, said parts operating substantially as described.

3. The combination with a log-carriage, of offsetting mechanism comprising block and knee devices supporting the log on the carriage, a rock-shaft with connections for reciprocating said block and knee devices, a pair of pivoted legs or levers, having extensible spring-pressed sections, friction shoes or heads pivoted to said extensible sections, a bar or rod tying together said shoes or heads, and connections between said bar or rod and said rock-shaft for oscillating the same, substantially as and for the purposes set forth.

4. The combination with a log-carriage, of an automatic offsetting device involving a pivoted leg or arm, made up of telescoping and longitudinally-adjustable spring-pressed sections, and a friction head or shoe pivoted to the extensible section of said leg and provided with connections to the log-supporting devices, which heads or shoes are adapted to slide over a longitudinal rail, substantially as described.

5. The combination with a log-carriage, of automatic offsetting mechanism involving the leg or arm a^3 with the telescoping sections a^4

and a^5 , the former adjustably secured by the brackets, the spring a^7 within the section a^4 acting on the extensible section a^5 and subject to the set-screw a^8 , and the friction shoe a^9 or head a^{10} pivoted to said section a^5 at a^{11} and provided with the friction block or brush a^{12} adapted to work over one of the track-rails, substantially as described.

In testimony whereof we affix our signatures in presence of two witnesses.

FRED H. MILLER.
PETER LARSON.
